US0D1028202S

(12) **United States Design Patent** (10) Patent No.: **US D1,028,202 S**
(45) Date of Patent: ** May 21, 2024

(54) **FILTER**

(71) Applicant: **The Procter & Gamble Company**,
Cincinnati, OH (US)

(72) Inventors: **Barry Howard Jacobs**, Princeton
Junction, NJ (US); **John Evan Spirk**,
Gates Mills, OH (US); **Danwei Ye**,
Solon, OH (US)

(73) Assignee: **The Procter & Gamble Company**,
Cincinnati, OH (US)

(**) Term: **15 Years**

(21) Appl. No.: **29/767,415**

(22) Filed: **Jan. 22, 2021**

(51) LOC (14) Cl. **23-04**

(52) U.S. Cl.

USPC **D23/365**

CLAIM

The ornamental design for a filter, as shown and described.

DESCRIPTION

FIG. 1 is a front perspective view of an embodiment of a filter;

FIG. 2 is a front view thereof;

FIG. 3 is a left view thereof;

FIG. 4 is a back view thereof;

FIG. 5 is a right view thereof;

FIG. 6 is a top view thereof; and,

FIG. 7 is a bottom view thereof.

The broken lines shown in the drawings illustrate portions of
the filter and form no part of the claim.

1 Claim, 4 Drawing Sheets
